PROCESS FOR THE REMOVAL OF MERCAPTANS FROM HYDROCARBON DISTILLATES

David Louis Yabroff, Berkeley, Calif., assignor to
Shell Development Company, San Francisco,
Calif., a corporation of Delaware

Application May 26, 1937, Serial No. 144,867

1 Claim. (Cl. 196—32)

This invention deals with the removal of mercaptans from their solutions in hydrocarbon type liquids by treating same with an aqueous alcoholic solution of an alkali metal hydroxide.

5 Petroleum distillates and, in particular, gasolines, containing an undesirable amount of mercaptans have a "sour" reaction and unpleasant odor. It is known that mercaptans can be oxidized readily to disulfides which are "sweet" 10 but have the disadvantage of reducing the knock-rating and lead susceptibility of gasoline toward tetra ethyl lead. For this reason, and because the sulfur content of gasolines should be reduced to a minimum, it is usually more 15 desirable to remove at least a major portion of the mercaptans by extraction, and if a small remainder thereof is left in the solution of the hydrocarbon oil, to subject the same to a known sweetening process as, for instance, by oxidation.

20 It is the purpose of this invention to describe a process for extracting mercaptans from hydrocarbon type liquids, particularly from gasoline distillates. It is another purpose to carry out this process under conditions of minimum loss 25 of treating material; and it is another purpose to produce a spent extracting reagent which can be recovered at a minimum cost.

My process consists essentially of extracting mercaptans from hydrocarbon type liquids containing same, but which are substantially free from acids other than mercaptans, with an aqueous methyl or ethyl alcoholic alkali metal hydroxide solution containing from 25 to 75% by volume of the alcohol, under conditions to form 30 two layers, a treated layer of hydrocarbon type liquid, and an alkali sludge layer containing mercaptides, and separating the layers. In order to remove mercaptans successfully it is necessary that the extraction be carried out in the absence 35 of oxidizing agents, which under the conditions of the treatment would oxidize the mercaptans to disulfides. Such oxidation would prevent a successful reduction of the sulfur content and would increase the content of undesirable disulfides. For this reason the extraction should 40 be carried out at substantially normal room temperatures, i. e., not above about 60° C., in the absence of free sulfur and also preferably in the absence of air.

45 The alcoholic alkali sludge layer obtained in the extraction is then regenerated by oxidation to convert mercaptides to disulfides. Disulfides are separated from the oxidized sludge and the latter is used to extract further quantities of 50 hydrocarbon type liquids containing mercaptans.

In order that the alkali sludge be regenerable for reuse, it is essential that the hydrocarbon type liquid be free from acids other than mercaptans, as no other acids can be removed from alkali hydroxide by simple oxidation to neutral 5 compounds. Water or dilute alkali wash is suitable for the removal of such acids from the hydrocarbon type liquid.

I am aware that it was known to treat hydrocarbon oils with sulfuric acid and thereafter with 10 aqueous alcoholic caustic containing about 50% alcohol, for the purpose of removing acid sludge dissolved in the oil. In this treatment mercaptans are largely dissolved in the sulfuric acid or are oxidized to disulfides so that in the subsequent treatment with alcoholic alkali hydroxide few, if any, mercaptans are removed. Moreover, the acid sludge in the oil produces a spent alkali sludge which is substantially non-regenerable because of the presence of sulfuric acid 15 esters, sulfonic acids and the like, and the free alkalinity of the alkali sludge is generally reduced to such a point, that its power to remove mercaptans is substantially lessened, if not completely destroyed. 25

I am also aware that ethyl and methyl alcohols have been used for the breaking of petroleum emulsions, as crude oil emulsions or emulsions of acid and alkali treated distillates. However, wherever such emulsions occur, the agent responsible for the emulsion contains an acid which is materially stronger than mercaptans, so that even if an aqueous alcoholic caustic of the required concentration would result, it would contain salts of acids which preclude a substantial 30 35 complete regeneration for the production of a recovered aqueous alcoholic alkali hydroxide suitable for the continued extraction of mercaptans.

I am further aware that petroleum distillates 40 containing mercaptans have been treated with alcoholic caustic containing less than about 15% water for the purpose of extracting the mercaptans. While this process is efficient as far as the removal of mercaptans is concerned, I have 45 found that substantially anhydrous alcoholic caustic solutions dissolve considerable quantities of hydrocarbon and like liquids, thereby causing losses thereof; and moreover the recovery of the spent alcoholic alkali hydroxide solution of low 50 content of water is usually accompanied by difficulties.

Heretofore it was believed that mercaptans could not be extracted efficiently from hydrocarbon type liquids with aqueous alcoholic caustic 55

- containing a substantial amount of water, i. e., more than about 15%, because it was believed that on account of the low acidity of the mercaptans water caused hydrolysis of mercaptides
- 5 to free mercaptans, which are preferentially soluble in the hydrocarbon type liquid. However, I have found that this view is erroneous. Generally speaking, the efficiency of extracting mercaptans from hydrocarbon type liquids increases
- 10 with both the concentrations of the alcohol and of the alkali hydroxide. Thus from the point of view of extraction efficiency alone, it may appear desirable to use substantially anhydrous alcohol, rather than aqueous alcohol, containing alkali
- 15 hydroxide. However, I have found that, whereas the percent mercaptans extracted increases rapidly with increasing alcohol concentrations up to about 50%, above this point further increases in the extraction of mercaptans are small, and
- 20 are insignificant above about 75% alcohol concentration. On the other hand, the loss of hydrocarbon type liquid in the alcoholic alkali hydroxide is very small up to about 50% alcohol concentration and then increases rapidly.
- 25 The effect of alcohol concentration on the extraction efficiency and loss of hydrocarbons into the extract phase is demonstrated in Fig. 1 and in Fig. 2, curve 2, respectively.

In Fig. 1 the percent mercaptans removed from

30 a solution thereof in iso-octane, when treating same with 10% by volume of dilute methyl alcoholic 5N sodium hydroxide in a single stage at 20° C. is plotted against the concentration of the alcohol in the sodium hydroxide solution. Four

35 pure mercaptans, namely, n-propyl, n-butyl, n-amyl and n-heptyl are represented by curves 1 to 4, respectively. As is clearly shown, a break occurs in each of these curves at about 50% alcohol concentration, the curves being very steep

40 at concentrations below that point but rapidly flattening out above it. At 75% alcohol concentration from 95 to 99% of the mercaptans are extracted and further concentrating the alcohol has at best the effect of removing the remaining

45 1 to 5%.

Against this relatively small improvement in mercaptan removal, which under many circumstances is quite insignificant, stands the loss of the hydrocarbons in the alcohol phase. In Fig. 50 2, curve 2, the concentration of methyl alcohol in 5N sodium hydroxide is plotted against volume percent of a typical gasoline absorbed by the alcoholic sodium hydroxide, when treating 75 parts of the gasoline with 5 parts of the hydroxide at

55 20° C. Up to about 50% concentration of methyl alcohol, little, if any, gasoline is absorbed, whereas above this point the absorption increases rapidly.

A further unfavorable effect of increasing concentration of the alcohol in the alkali metal hydroxide solution is its effect on the color of the hydrocarbon type liquid to be treated. Alcoholic alkali metal hydroxide, besides extracting mercaptans, apparently is capable of effecting condensation and the like reactions, resulting in the formation of colored products, many of which are soluble in the hydrocarbon type liquids to a considerable extent. The extent of these condensation reactions is increased with increasing concentration of the alcohol. Thus, I have found that upon agitating a raw California cracked gasoline for several minutes with 10% by volume of sodium hydroxide solutions of varying methyl alcohol concentrations, then separating the so-

70 75

latter with water and diluting it with 3 parts by volume of a gasoline having a 30+ color on the Saybolt colorimeter, the following colors were obtained:

Treatment	Color of blend, Saybolt colorimeter	5
None		
5N NaOH in water	+19	
5N NaOH in 50% aqueous methyl alcohol	+16	10
5N NaOH in 90% aqueous methyl alcohol	+8	
5N NaOH in 100% methyl alcohol	+3	
	-12	

It has been stated hereinbefore that one of the important features of this process consists of regenerating the alkali sludge, and it has been pointed out that the absence of acids other than mercaptans is essential for that purpose. I have now found that in order to enable regeneration of the alkali sludge a further limitation must be imposed thereon; i. e., I have found that the economical regeneration may become difficult, if not impossible, if the concentration of the alcohol in the alkali sludge is too high.

The usual method of regenerating alkali sludges used in the extraction of mercaptans consists of steaming or oxidizing same with air. Alkali hydroxides containing alcohols, however, cannot readily be steamed because of the volatility of the alcohols and their ready solubility in water. Moreover, mercaptans which are removed overhead in the steaming, together with the alcohol, are considerably soluble even in relatively dilute aqueous alcohols, so that separation of the two would be extremely difficult. It therefore appears that oxidation is the only practical means for regenerating the alcoholic alkali sludge.

Upon oxidation, mercaptides are converted to disulfides which can be separated from the aqueous alcoholic alkali metal hydroxide. Here again I found that the completeness of separating the disulfides depends largely on the concentration of the alcohol, disulfides being considerably soluble in alcohols of high concentrations. The trends in the solubilities of disulfides in aqueous alkali metal hydroxides of varying contents of alcohol are very similar to those for gasoline and can be represented by curves such as curve 2 in Fig. 2, which shows that up to concentrations of about 50% alcohol the solubilities of disulfides are quite low but that above this point they rapidly increase. When the concentration of alcohol is materially higher than about 75%, frequently no separation at all of disulfides takes place, all of the disulfides formed being soluble. While dissolved disulfides can be removed by scrubbing the oxidized alkali sludge with a hydrocarbon solvent or the like, such scrubbing is undesirable, because it not only adds several extra steps to the treatment, but also results in the loss of some alcohol since alcohols containing 55 60 65 70 75 80 85 90 95 water are considerably soluble in hydrocarbon solvents. On the other hand, if the oxidized regenerated alkali sludge containing substantial amounts of disulfides is used to extract further quantities of mercaptans from hydrocarbon type liquids, the disulfides contained therein are reintroduced into the hydrocarbon type liquid, with the effect that the purpose of removing mercaptans rather than converting them to disulfides may be completely negated.

The curves in Fig. 2 graphically illustrate the effect of the concentration of alcohol on the removal of mercaptans and the return of disulfides,

75

when treating California cracked gasoline, having an original mercaptan sulfur content of .162%, with 5N methyl alcoholic sodium hydroxide which has been regenerated by oxidation, disulfides having been separated by skimming. The volume ratio of gasoline to alcoholic sodium hydroxide solution was 15 to 1 throughout the tests.

Curve 1 shows the removal of mercaptans, as read on the left hand scale. As will be noted, 10 that curve closely resembles the curves of Fig. 1. Curve 2 is the solubility curve for the disulfides in the alcoholic hydroxide in terms of the right hand scale. From this curve, curve 3 has been 15 calculated, showing the amount of disulfide sulfur which is returned with every part of regenerated alkali sludge in percent of the gasoline to which it is returned as read on the left hand scale. Curve 4 finally is compounded from curves 1 and 3 and shows the sum of mercaptan and 20 disulfide sulfur in the gasoline after treatment. It is seen that for this particular gasoline the optimum concentration of alcohol which results in the lowest sulfur content is between 50 and 60%. This optimum may vary somewhat for different 25 gasolines.

If, instead of merely skimming the oxidized solution to remove disulfides, scrubbing is resorted to, curve 3 is moved to the right. Since, 30 however, in the scrubbing the loss of alcohol must be balanced against the scrubbing efficiency in removing the disulfides, both of which are unfavorably influenced by increasing alcohol concentration, I have found that the optimum alcohol 35 concentration usually remains below 75% and always below 85%.

The oxidation for the purpose of regeneration must be carried out under conditions to convert mercaptans to disulfides, while substantially suppressing the formation of sulfonic acids and the 40 oxidation of the alcohol. I have found that the desired oxidation can be effected satisfactorily by agitating the alcoholic alkali hydroxide with a moderate excess of air at about normal room temperature, preferably between 45 about 20° to 50° C. and in the presence of a catalyst known to promote the oxidation of mercaptans or mercaptides to disulfides, examples of such catalyst being PbO, PbS, NiO, NiS, CoO, CoS, CuO, CuS, etc. The rate of the oxidation 50 increases with increasing oxygen pressure and temperature. If air is used the air pressure maintained on the system in advantageously between about 15 to 30 pounds absolute.

In general the amount of oxygen absorbed is 55 substantially independent of temperature and pressure within the above limits but increases with both the concentrations of the alcohol and of the alkali metal hydroxide.

At low concentrations of alcohol and alkali 60 metal hydroxide the amount of oxygen is about 25 to 30% in excess of that required to convert all of the mercaptides to disulfides. Since the oxidized solution normally contains no aldehydes or fatty acids which might be formed by oxidation 65 of the alcohol, it appears that this excess oxygen is used largely to convert a small portion of the mercaptans to sulfonic acids. Obviously, in order to enable a utilization of the alkali hydroxide over an extended period of time this oxidation 70 to sulfonic acids must be maintained at a minimum. Variations in the concentration of the alkali metal hydroxide seem to have relatively little effect in the region of low concentration up to about 2 mols per liter less than saturation. 75 Thus when oxidizing under the above described

conditions a series of sodium hydroxides of varying normalities, containing 50% alcohol and mercaptides, the following amounts of oxygen in percent of the theoretical amount required to convert the mercaptides to disulfides, were absorbed:

Normality of NaOH	Oxygen absorbed per cent of theoretical amount to form disulfides
2.5	125
5	130
7	155
7.3 (saturated)	160
	15

Within the suitable range of alkali metal hydroxide concentration of 2 mols per liter less than saturation the influence of the concentration of the alcohol up to about 75% is small. While there is no noticeable difference in the oxygen consumption with variations in the alcohol concentrations below about 50%, there are usually some variations between 50 and 75% alcohol concentrations. In general, from a purely practical standpoint it is therefore desirable to keep the alcohol concentration below about 75%, particularly at relatively high concentrations of alkali metal hydroxide which for the efficient extraction of mercaptans are desirable.

The influence of the concentration of the alcohol on the oxygen absorption is well illustrated by the following data:

Concentration of methyl alcohol in 5NaOH	Oxygen absorption in per cent of theoretical amount to form disulfides
0	125
25	125
50	130
75	150
100	200

From the above it is seen that when considering the various aspects which affect the efficiency of mercaptan removal from hydrocarbon type liquids with alcoholic alkali metal hydroxides, it is advantageous to employ solutions containing substantial amounts of water. The alcohol concentration should be between the limits of about 25 to 75% and preferably between about 50 to 60%; and the alkali metal hydroxide concentration should be as high as possible, preferably above 2 normal, but below about 2 mols per liter below the saturation point at normal room temperature.

When herein speaking of alcohol concentration I refer to the ratio of alcohol to water and do not take into account the amount of alkali metal hydroxide added. For instance, a 5N—NaOH solution containing 60% alcohol means a mixture of 40% water and 60% alcohol in which 5 mols per liter of NaOH have been dissolved.

While in the foregoing examples methyl alcohol has been used exclusively, I have found that ethyl alcohol can be used instead. Solubility relations are similar except that at relatively higher concentrations of alcohol conditions are even less favorable than for methyl alcohol, ethyl alcohol causing greater losses of hydrocarbon type liquids, more discolorization, and is more readily miscible with disulfides. Moreover, its susceptibility to oxidation, particularly at high concentrations above about 75%, is quite pronounced. Higher alcohols, such as propyl, butyl, etc., alco-

- hols, are too soluble in hydrocarbon type liquids to be of practical value and moreover, are readily salted out from their aqueous solutions by alkali metal hydroxides.
- 5 Although the hydrocarbon type liquids hereinbefore mentioned are either gasoline distillates or pure hydrocarbons, the process is not restricted to them. Any organic liquid which is substantially immiscible with water, is neutral or 10 slightly basic, resistant to the action of strong alkali hydroxide at ordinary temperatures and substantially resistant to oxidation under the conditions hereinbefore described, may be treated by this process to separate mercaptans therefrom.
- 15 The term hydrocarbon type liquids as herein used is therefore meant to include, aside from mineral oil distillates, organic liquids such as coal tar distillates, benzene, toluene, xylene, pentanes, hexanes, chlorinated hydrocarbons of which carbon 20 tetrachloride, chlor ethane, ethylene di-chloride, tri chlor ethylene, tetra chlor ethane, chlor propanes, etc., are examples, petroleum bases, quinoline, etc. The term, however, does not include aqueous emulsions containing more than traces 25 of water because water in the hydrocarbon type liquid changes the concentration of the alcohol in the resulting alkali sludge, which as has been shown must be kept between definite limits for optimum operation.
- 30 While in the foregoing description of regenerating alkali sludge by oxidation I have described

air oxidation only, it shall be understood that other mild oxidation methods may be used instead. For instance, electrolytic oxidation under carefully controlled conditions so as to prevent formation of sulfonic acids, as described in the Yabroff and Givens application, Serial Number 96,708, filed August 19, 1936, may be applicable under many circumstances.

I claim as my invention:

In a regenerative process for desulfurizing a 10 hydrocarbon liquid which contains mercaptans and is substantially free from acids other than mercaptans, which process involves extraction of mercaptans from said oil with an alcoholic aqueous solution of an alkali metal hydroxide, where- 15 by a treated hydrocarbon liquid and a spent solution containing mercaptides are formed, regenerating said spent solution by air blowing under conditions to oxidize mercaptides to disulfides at least a portion of which form a separate layer 20 which is removed, and extracting more of said oil with the resulting regenerated solution having essentially the same composition of the original aqueous solution, the improvement comprising employing in said extraction a solution consisting essentially of 50 to 60% of an alcohol selected from the group consisting of methyl and ethyl alcohols, at least 25% water and an alkali metal hydroxide.

DAVID LOUIS YABROFF. 30
